UNITED STATES PATENT OFFICE.

RICHARD S. BROGE, OF CHICAGO, ILLINOIS.

AUTOMATIC BOOT CLEANER.

Application filed April 3, 1925. Serial No. 20,370.

To all whom it may concern:

Be it known that I, RICHARD S. BROGE, a citizen of the United States, and resident of Chicago, in the county of Cook and State 5 of Illinois, have invented certain new and useful Improvements in an Automatic Boot Cleaner, of which the following is a specification.

This invention relates to improvements 10 in an apparatus for automatically cleaning the shod feet of persons, or, rather, removing dirt, dust, mud, and the like from the shoes or footwear, as they walk upon the device on entering a room, hall, school 15 building, theatre, church, or even a private residence, if desired.

The invention has for one of its objects the provision of an automatic boot cleaner, which shall be simple and inexpensive in 20 construction, strong, durable and highly efficient in operation, which shall be of such construction, arrangement and combination of its parts as to be readily installed in a path to be trod by persons or pedestrians, 25 such as, at the threshold or entrance to a building, in front of the threshold, for example, in a vestibule or lobby, or inwardly of the threshold, as within the room being entered, in such a way as to be unnoticeable 30 and without offering any interference or danger to those walking on the same.

Another object is to furnish a boot cleaning device of such characteristics in its construction and arrangement of its parts 35 as to require no effort or attention on the part of persons treading the path in which it is located, other than the usual effort exerted in walking, and perhaps enough attention to see that each foot shall be 40 placed on the supporting bars of the device, in order that each may be cleaned.

Still another object is, the provision of a boot cleaner, the parts of which shall be of such material, construction and operation 45 as to thoroughly and quickly clean the soles or lower portion of the shoes without injuring or marring them.

A still further object is the provision of a boot cleaner of a highly sanitary character, 50 that is to say, one of such construction that but little if any dust or dirt removed from the shoes in the act of cleaning them, will escape from the container of the apparatus, but on the other hand will be confined 55 therein and deposited into a removable receptacle, by means of which the deposit

can be discharged into a furnace or otherwise disposed of.

Still a further object is the provision of auxiliary means for automatically cleaning 60 the main cleaning elements.

Furthermore, to provide means for readily adjusting the positions of the main cleaning elements with respect to the tread portion of the device and for adjusting the 65 position of one of the shafts for the main cleaning elements with respect to the other shaft therefor.

Other objects and advantages of the invention will be disclosed in the following 70 description and explanation, which will be more readily understood when read in conjunction with the accompanying drawings, in which an embodiment of the invention is illustrated, it being understood that changes 75 and modifications may be resorted to without a departure from the spirit of the invention, so long as they fall within the scope of the appended claims forming a 80 part hereof.

In the drawings,—

Fig. 1 is a plan view of the device showing it mounted in a suitable opening in a horizontally disposed floor or platform so 85 as to be about flush therewith.

Fig. 2 is a vertical sectional view taken on line 2—2 of Fig. 1 looking in the direction indicated by the arrows showing the cleaning elements and tread members of the device in about their normal positions.

Fig. 3 is a vertical sectional view taken on line 3—3 of Fig. 1 looking in the direction indicated by the arrows showing the driving mechanism for the various parts of the device, the means for adjusting the shafts of 90 said mechanism, and illustrating means for automatically starting and stopping the electric motor which drives said mechanism.

Fig. 4 is a transverse vertical sectional view taken on line 4—4 of Fig. 1 looking 100 in the direction indicated by the arrows, and

Fig. 5 is a plan view of a portion of one end of the frame of the device showing means for adjusting the positions of the shafts of the driving mechanism and illustrating a part of the cleaning elements and tread portion of the device.

Corresponding numerals of reference refer to like parts throughout the different 110 views of the drawings.

The reference numeral 10 designates a portion of a horizontally disposed floor or

platform, such as the floor of a building, which is provided with an opening 11 rectangular in shape and of any suitable size, but usually of about the same width as the 5 door-way to the room or hall in connection with which the device is used, and of sufficient length as to require at least two steps by the persons entering the room to cross the same with his feet in contact with the 10 tread portion of the device in order that each shoe shall be exposed or subjected to the cleaning elements of the device for a short length of time. The main frame is indicated as a whole by the numeral 12 and 15 is of a shape and size to correspond with the shape of the opening 11 and to fit snugly yet vertically movable therein. This frame may be of any suitable material but usually of wood and box-like in construction, and 20 is supported at each of its corners by means of a spring 13 interposed between a suitable supporting base 14 and the bottom of the frame, as will be readily understood by reference to Figs. 2, 3, and 4 of the drawings. The springs 13 are employed to hold the main frame 12 normally with its upper surface about flush with the surface of the floor or platform, especially so at the sides thereof. The end portions of the frame 12, 25 see Fig. 4, are by preference disposed at their upper edges a slight distance below the surface of the floor 10 for the purpose of permitting a guard board or member 15 to rest on the upper portion of each of said 30 end pieces so as to be flush with the surface of the floor or platform and to extend inwardly a slight distance with respect to the frame 12 in an upwardly inclined position, in which position each of said members 35 will be normally maintained by means of coil springs 16 interposed between said members and the upper portion of the frame 12 near each side thereof.

In order to read the drawings properly, 40 it will be understood that the top of the view shown in Fig. 1 represents the entrance end of the device and the lower part of said view of the other or exit end of the main frame. The frame 12 is provided on the 45 inner surface of its front or entrance end piece and its rear or exit end piece with a pair of spaced vertically disposed guide-ways 17 and 18 preferably of dove tail formation as shown in Fig. 5 of the drawings, 50 which guide-ways are for the reception and operation of bearing plates or blocks 19 and 20 respectively for the shafts of the cleaning elements carrying mechanism of the device. The lower end of each of the 55 blocks 19 and 20 is beveled as at 21, see Fig. 3, to co-act with beveled portions 22 on the upper surface of a bar 23 slidably mounted on the lower inner surface of each of the said end pieces and each having at one of its ends a rack bar 24 to en-

gage pinions 25 mounted on a shaft 26 journaled near its ends in the lower part of said end pieces of the frame near one of their corners, as is clearly shown in Fig. 3 of the drawings. This shaft 26 has one 70 of its ends extended through one of the end pieces of the main frame and formed to engage a wrench to be used for turning the same when it is desired to elevate or lower the adjustable blocks or plates 19 and 20 75 and through them the shafts of the mechanism for the cleaning elements. Each of the blocks or bearing plates 20 is provided near its upper end with a horizontally disposed recess 27 in which is slidably mounted a block 28 which has at its outer end a laterally extending arm 29 provided with a screw-threaded opening to engage a screw-threaded bolt 30 extended through a suitable opening on one of the side walls 80 of the main frame near each of its ends. 85 Journaled at its ends in the adjustable or slideable blocks 28 and between the same is a shaft 31 which assists in the support and operation of the cleaning elements of the 90 device, as will be presently explained.

A vertically and transversely disposed partition 32 located a slight distance inwardly from the front end piece of the main frame and in parallelism therewith provides a compartment for the gearing uniting the various shafts of the mechanism for the cleaning elements and prevents the same being exposed to dust and dirt removed from the shoes in the cleaning operation thereof. This partition is provided with an opening 33 near one of its ends through which the shaft 31 is extended and said opening is of such dimensions as to permit of considerable vertical movement 100 of said shaft without interference therewith. Near its other end the partition 32 is provided with a vertical slot 34 through which the driving shaft 35 of the main cleaning elements is extended at one of its 105 ends, said end being journaled in the adjustable block 19 mounted on the front end piece of the main frame.

Near the rear end piece of the main frame at a slight distance inwardly thereof said frame is provided with another vertically disposed partition 36 which is provided with an opening 33 near one of its ends and with a vertical slot 34 near its other end for the reception and operation of the shafts 31 110 and 35 respectively, which shafts are journaled at their ends adjacent the partition 36 in the blocks 20 and 19 respectively of the rear end piece of the main frame.

Extended through suitable vertical slots 37 in the portion of the partitions 32 and 36 adjacent the shaft 26 is a shaft 38 which is journaled at its ends in the blocks 19 near the lower ends thereof as will be clearly seen in Fig. 4 of the drawings. Extended 115 120 125 130

through vertical slots 39 in each of the partitions 32 and 36 adjacent the shaft 31 is a shaft 40 which is journaled at its ends in the blocks 20 near the lower ends thereof. 5 Each of the shafts 38 and 40 has mounted thereon within the compartment formed by the partition 32 and the front end wall of the main frame a pulley 41 over which is extended an endless belt 42 for rotating said shafts. 10 Each of the shafts 38 and 40 is provided between the partitions 32 and 36 with radially disposed bristles 43 of any desired kind and secured to said shafts in any well known way. These bristles or 15 brushes may be termed auxiliary cleaners or elements, and co-act with the main cleaning elements for cleaning the latter in a manner to be hereinafter explained.

Mounted on the driving shaft 35 to turn therewith and between the partitions 32 and 36 is a drum or roller 44 which is provided with a series of spaced circumferentially disposed grooves 45 for the reception and operation of a series of tread members 25 or bars 46 which are by preference made of metal and extend from one of the sides of the main frame 12 to the other side thereof, see Figs. 1, 2 and 5 of the drawings. These tread members or bars 46 present their 30 edges vertically and are supported at their ends each by a pair of coil springs 47 nested in vertical openings 48 arranged in spaced relation with one another in the sides of the main frame, each of which sides is provided in its upper inner portion with a 35 series of spaced vertical slots 49, see Fig. 2, which slots not only afford guide-ways for the bars 46 but also furnish means to restrict the downward movement of said bars 40 when the latter are stepped upon. By the foregoing arrangement it is manifest that the tread members or bars 46 will be held in spaced relation to one another and for vertical movement by means of the slots 49 and the grooves 45 in the roller 44 with 45 which grooves said slots register.

Mounted on the shaft 31, which shaft may be an idler, and between the partitions 32 and 36 is a drum or roller 50 of the same 50 construction as the roller 44 and above described. Extended over the rollers 44 and 50 between each pair of the tread members or bars 46 is an endless belt 51 which is provided on its outer surface with a series of bristles 52 of any suitable kind and in any well known way so as to provide an endless brush-like formation to be presented to the soles or lower parts of the shoes worn by persons as they walk upon and over the 55 tread members of the device. The shaft 38 has mounted thereon within the compartment 53 formed by the partition 32 and the front end wall of the main frame a gear 55 journaled 60 which meshes with a pinion 55 journaled on a stub shaft 56 extended inwardly from

the block 19 of the front end wall of the main frame, which pinion meshes with a gear 57 mounted within said compartment on the driving shaft 35, which driving shaft is connected to an electric motor 58 for 70 driving the same by means of a chain belt 59 extended over a sprocket or pulley 60 on the shaft 35 and over the shaft of the motor in a well known way. This chain is extended through a suitable opening 61 in 75 one of the sides of the main frame and said motor is by preference mounted on a bracket 62 secured to said side of the main frame. Leading from the field of the motor is a flexible conductor 63 which is connected to 80 a contact member 64 carried by the main frame and employed for co-operation with a contact member 65 mounted on the base or support 14 and having connection through a flexible conductor 66 with the 85 armature of the motor. The contact members 64 and 65 also have connection through conductor 67 with a supply of electricity.

By this arrangement it is apparent that as the main frame of the device is supported 90 on the springs 13 for vertical movement, as soon as said frame is depressed by a person stepping upon the tread bars or members thereof, the member 64 will contact with the member 65, thus causing the motor to be 95 energized and through it and its gearing drive the mechanism carrying the cleaning elements. Furthermore, as soon as pressure is removed from the tread members of the device or the main frame it is obvious that 100 the springs 13 will react and thus cause the contact members 64 and 65 to be separated and the electric circuit broken, to the end that the operation of the device will 105 cease.

As the tread members 46 normally extend a slight distance above the plane of the floor or platform 10, and as this protrusion might trip or cause pedestrians to stumble in walking across the bars 46, the spring supported and slightly inclined guard members or plates 15 are employed, as it is obvious they will prevent the feet of persons coming in abrupt contact with the outermost bars or tread members. 110

In the event the bristles or shoe cleaning elements 42 become worn or shortened from use and it is desired to elevate the drums or rollers 40 and 50 so as to elevate said cleaning elements to a point about normally flush 115 with the upper edges of the tread members 46, it is manifest that by turning the shaft 26 in the proper direction, the wedge-shaped portions 22 of the bar 23 will co-act with the bearing blocks 19 and 20 in such a way as to raise them and consequently the said rollers which are journaled on said blocks. Should the endless belts 51 carrying the 120 cleaning elements 52 become slack and it is desired to tighten the same, this can be 125

readily done by turning each of the screws 30 in the proper direction to cause the adjustable plates or members 28 to be moved outwardly as is apparent.

5 From the foregoing and by reference to the drawings it will be readily understood and clearly seen that by my improvements a foot cleaning apparatus of a very efficient character is provided for cleaning the shoes 10 of persons or pedestrians as they enter a building and walk on and over the tread members of the device, and that by reason of the construction and arrangement of the parts as above set forth and shown in the 15 drawings the dirt and dust removed from the shoes will be to a great extent prevented from escaping into the room, but will be deposited into the lower part of the main frame which may be equipped with a drawer 20 70 which can be removed through a suitable opening in the main frame.

By reference to Figs. 1 and 2 of the drawings, it will be seen and understood that each of the tread members 46 is provided at 25 each of its ends with a longitudinally extended reduced portion, which portions are located adjacent the sides of the main frame and have resting thereon boards 71, which boards may be secured at their outer edges 30 to the sides of the main frame in any well known way and are employed to restrict the upward movement of the tread member 46 incident to the pressure of the springs 47 on which they rest.

35 Having thus fully described my invention, what I claim as new and desire to secure by Letters Patent is:

1. In a boot cleaner, the combination with 40 a platform or floor having an opening therein, of a main frame mounted in said opening with its upper portion almost flush therewith, a yieldingly supported guard plate mounted at each end of said frame and extended inwardly and upwardly over a portion thereof, a plurality of spaced tread members 45 depressedly mounted in the upper portion of said frame and vertically guided thereby, said members being normally disposed at their upper edges in a horizontal 50 plane with the upper portions of said guard members when the latter are in their normal positions, elongated shoe cleaning elements mounted for longitudinal movement between pairs of said members, and means for 55 driving said elements.

2. In an automatic boot cleaner, the combination with a main frame mounted for 60 vertical movement, of an electric motor, a switch for making and breaking an electric circuit to said motor upon the depression and elevation respectively of the main frame, a plurality of spaced tread members horizontally and depressedly mounted in the upper portion of the main frame, elongated shoe 65 cleaning elements mounted for longitudinal

movement between pairs of said members, and means operable by said motor for driving said elements.

3. A boot cleaner including in combination, 70 an open top main frame having in the upper portion of each of its sides a plurality of spaced and vertically disposed openings, a coil spring in each of said openings, each of said sides of the frame having at 75 its upper edge a vertical slot communicating with each of said openings but terminating short of the length of said openings, a tread member or bar horizontally mounted between the sides of the frame in a pair 80 of said slots and supported by a pair of said springs, and means overlying the ends of said bars and carried by the sides of the frame for restricting the upward movement of said bars.

4. In a boot cleaner, the combination with 85 a platform or floor having an opening therein, of an open top main frame mounted in said opening with its upper portion almost flush therewith, a yieldingly supported guard 90 plate mounted at each end of said frame and extended inwardly and upwardly over a portion thereof, each side of the main frame having in its upper portion a plurality of spaced and vertically disposed openings, a 95 coil spring in each of said openings, each of said sides of the frame having at its upper edge a vertical slot communicating with each of said openings but terminating short of the length of said openings, a tread member 100 or bar horizontally mounted between the sides of the frame in each pair of said slots and supported by a pair of said springs, and means overlying the ends of said bars and carried by the sides of the frame for 105 restricting the upward movement of said bars.

5. In a boot cleaner, the combination with 110 a platform or floor having an opening therein, of an open top main frame mounted in said opening with its upper portion almost flush with the upper surface of said platform, a pair of spaced rollers horizontally journaled on and between the ends of the main frame and located in parallelism with one another near its upper portion, each of 115 said rollers having a plurality of spaced circumferential grooves therein, a plurality of spaced tread members transversely mounted between and yieldingly supported at the upper portions of the sides of said frame and 120 located in said circumferential grooves of said rollers, an endless belt extended around the said rollers between pairs of said tread members and each having on its outer surface shoe cleaning means, and means for 125 driving said rollers.

6. In a boot cleaner, the combination with 130 a platform or floor having an opening therein, of an open top main frame mounted in said opening with its upper portion almost

- flush with the upper surface of said platform, a pair of spaced rollers horizontally and vertically adjustably journaled on and between the ends of the main frame and located in parallelism with one another near its upper portion, each of said rollers having a plurality of spaced circumferential grooves therein, a plurality of spaced tread members transversely and horizontally 50 arranged for making and breaking an electric circuit to said motor upon the depression and elevation respectively of the main frame, a pair of spaced rollers horizontally journaled on and between the ends of the main frame, and located in parallelism with one another near its upper portion, each of 55 said rollers having a plurality of spaced circumferential grooves therein, a plurality of spaced tread members horizontally and transversely mounted between and yieldingly supported at the upper portions of 60 the sides of said frame and located in said circumferential grooves of said rollers, an endless belt extended around the said rollers between pairs of said members and each having on its outer surface shoe cleaning means, and means for driving said rollers. 65
7. In a boot cleaner, the combination with a platform or floor having an opening therein, of an open top main frame mounted in said opening with its upper portion almost flush with the upper surface of said platform, a pair of spaced rollers horizontally journaled on and between the ends of the 70 main frame and located in parallelism with one another near its upper portion, each of said rollers having a plurality of spaced circumferential grooves therein, a plurality of spaced tread members horizontally and transversely mounted between and yieldingly supported at the upper portions of 75 the sides of said frame and located in said circumferential grooves of said rollers, the upper edges of said members being normally disposed a slight distance above the upper surface of the platform, a yieldingly supported guard plate mounted at each end of said frame and extended inwardly and upwardly over a portion thereof and about flush with the normal position of the said 80 tread members, an endless belt extended around the said rollers between pairs of said tread members and each having on its outer surface shoe cleaning means, and means for driving said rollers. 85
8. In an automatic boot cleaner, the combination with a main frame mounted for vertical movement, of an electric motor, a switch
9. A boot cleaner including in combination a main frame having in opposed walls thereof vertical guide-ways, a bearing block mounted for vertical movement in each of said guide-ways, a shaft journaled in said blocks, a horizontally disposed bar mounted for longitudinal movement and having a beveled portion for co-operation with the lower portion of each of said blocks for raising the same, and means for reciprocating said bars. 90
10. A boot cleaner including in combination a main frame having in opposed walls thereof vertical guide-ways, a bearing block mounted for vertical movement in each of said guide-ways, a bearing plate mounted on each of said blocks for horizontal movement and each having an apertured arm extended laterally therefrom, a screw-bolt extended through a wall of the main frame and engaging the opening in each of said arms, a shaft journaled in said bearing plates, and a horizontally disposed bar mounted for longitudinal movement and having a beveled portion for co-operation with the lower portion of each of said blocks for raising the same, and means for reciprocating said bars. 95

RICHARD S. BROGE.
